UNITED STATES PATENT OFFICE.

PHILIP NEARY, OF WALLA WALLA, WASHINGTON.

PORTABLE HOPPER.

Application filed October 1, 1920. Serial No. 414,144.

To all whom it may concern:

Be it known that I, PHILIP NEARY, a citizen of the United States, and residing at Walla Walla, in the county of Walla Walla 5 and State of Washington, have invented certain new and useful Improvements in Portable Hoppers, of which the following is a specification.

This invention relates to an improvement 10 in material containing hoppers, constructed primarily with a view to ready assembling when desired for use, and as equally convenient separation of the parts to facilitate transportation, when the hopper is to be 15 moved from place to place.

The improved hopper is constructed in substantially similar sections, each made up of more or less permanently connected parts, with the respective sections adapted for 20 ready connection into hopper form, or disconnection into substantially flat sections, as may be desired.

In the drawings:—

Fig. 1 is an end elevation of the improved 25 hopper.

Fig. 2 is a side elevation of the same.

Fig. 3 is a vertical section on the line 3—3 of Fig. 2.

Fig. 4 is an elevation of one of the sections.

Fig. 5 is a detail view of the discharge 30 chute.

The improved hopper is preferably constructed of wood strips or sections of appropriate length and cross-section, and each 35 section includes a base, comprising bottom strips 1, from which rise vertical strips 3, connected at the upper end by cross strips 4. Braces 5 maintain a rigid base structure. A supporting strip 6 extends transversely 40 of the upper end of the base, and secured on such strip 6 is a bearing strip 7, such strip 7 extending upwardly at an angle to the strip 6, and being held by braces 8. An upright 9 rises from the strip 6, extending upwardly past the strip 7 to the desired height 45 of the hopper.

Strips 11 are secured above the strip 7, through stringers 22, the said strips being in parallel relation to each other and to the 50 strip 7, and being spaced apart to form a channel to receive the side walls of the hopper. Floor boards 17 are secured to the transverse stringers 22 fixed on the strips 7.

The base portions, of which there are two 55 on each side of the hopper are rigidly secured on bottom struts 20, and braced rela-

tive to each other in a convenient manner. The base portions are so arranged that the lower ends of the strips 7 may be rigidly connected together, so that there is thus provided one side of the hopper made up of the divergent outline of the end walls. The other side is similarly assembled, and the braces 21 are arranged to hold them in this spaced relation.

Transverse stringers 22 are now bolted to the strips 7, these strips forming the outer supports for the floor boards. The upper ends of the uprights 9 are connected on each side by longitudinal strips 23, secured by 60 bolts, such strips 23, being arranged in pairs form the upper channel for the side boards of the hopper.

When assembled as described the floor boards 17 are placed on the stringers 22, 75 forming the front and rear walls of the hopper. One of such boards, as 25, is extended below the normal meeting lines of the floor boards to form a chute 26, such chute having side walls 27 secured thereto, the opposing 80 bottom board resting at its lowest end on the upper ends of the chute side walls 27, thus providing a discharge opening and chute at the lowest point of the hopper.

The side walls of the hopper, which may 85 also be made up of loosely placed board sections, are simply positioned by being passed between the upper guideways provided by the strips 23 and extended to and between the lower guideways provided by 90 the strips 11.

To prevent separation of the end walls of the hopper, there are provided tie members 28, preferably in the form of sectional rods connected by turnbuckles 29. The terminals of the tie members are removably secured to the strips 7, as by nuts engaging the threaded ends of the rods beyond the strips, the turnbuckles being tightened to 95 maintain a rigid bracing effect between the 100 end walls of the hopper.

The chute outlet which is in the form of a rectangular box-like conduit is adapted to be closed at one end by a plate 30, which is pivotally supported at 31 and adapted to 105 be moved by a lever 32 into a position across the end of the chute to close the same or in a position beyond said end to open the same. A screen partition 33 may, if desired, be arranged in the chute adjacent the outlet, 110 so as to screen the material.

From the above description it will be ap-

parent that the improved hopper is constructed in conveniently portable sections, which may be readily assembled or disconnected when desired, in order that the hopper may be set up convenient to the work in hand, and removed when not desired for use, or for use at another locality. The invention not only saves labor in building and breaking up hoppers of this type, as usually constructed, but also is a material saving in lumber, as no parts are lost or broken, and the hopper disconnected in one locality may be readily set up in another.

Having thus described the invention, what is claimed as new, is:—

1. A hopper structure, comprising a plurality of sections adapted to be secured together to provide a hopper frame, each section including a base, a supporting strip arranged thereon, side-wall receiving strips secured in spaced parallel relation on the supporting strip, and an upright rising from the supporting strip to hold the upper ends of the side walls.
- 25 2. A wooden hopper construction, comprising a plurality of base sections connected together, each base portion having an inclined wall supporting section, the meeting ends of such sections being secured

together, floor supporting strips extending 30 longitudinally of each section, cross-strips removably secured on such supporting strips, and floor boards loosely placed on such cross strips.

3. A hopper construction including base 35 sections each including inclined wall receiving strips, uprights, means for securing the meeting ends of the wall receiving strips together, spaced strips connecting the uprights to receive the upper ends of the hopper walls, and boards loosely placed between said spaced strips and the wall receiving strips.

4. A hopper construction comprising base 45 portions, side wall receiving strips carried by said base portions, means for removably connecting the meeting ends of said strips, uprights rising from the base portions, spaced strips connecting the uprights of adjacent base portions, and tie rods connecting the side wall receiving strips of one base portion with the side wall receiving strips of the adjacent base portion.

In testimony whereof I affix my signature in the presence of a witness.

PHILIP NEARY.

Witness:

T. V. WEBSTER.
